Inventor
Gustav Spannagel,

No. 893,029

UNITED STATES PATENT OFFICE.

GUSTAV SPANNAGEL, OF LIMA, OHIO.

BUNG-EXTRACTOR.

No. 893,029.

Specification of Letters Patent.

Patented July 14, 1908.

Application filed July 3, 1906. Serial No. 324,629.

To all whom it may concern:

Be it known that I, GUSTAV SPANNAGEL, a citizen of the United States, residing at Lima, in the county of Allen and State of Ohio, have invented certain new and useful Improvements in Bung-Extractors; and I do hereby declare the following to be a full, clear, and exact description of the invention, such as will enable others skilled in the art 10 to which it appertains to make and use the same.

The object of this invention is to provide an instrument to facilitate the removal of bungs from barrels.

15 The invention consists in the construction hereinafter described and claimed, the invention, in its practical embodiment, not being confined to the exact exemplification appearing in the accompanying drawings.

20 In said drawings—Figure 1 is a view in side elevation, the staff being partially broken out; and Fig. 2 is a detail in section on a larger scale.

In the views 1 designates the staff. This 25 is conveniently of tubular form and is provided with an enlarged externally threaded portion 1^a at its lower end. Threaded onto the portion 1^a is a chamber piece 2 which contains an electric-lamp socket device 3 of 30 ordinary or suitable construction.

4 Designates an incandescent electric lamp which preferably removably engages the socket 3. Between the socket and the lamp I place a cushion 5 of rubber or other suitable 35 material to prevent fracture of the lamp when the device is used.

The lower end of the chamber piece 2 is externally threaded, and onto this I thread a collar 6 having a caging or open work 7 and a 40 spike 8. The lamp is confined within the caging and thereby protected from injury without materially interfering with the illuminating function of the lamp.

It will be observed that, by the construction 45 as described, the lamp lies in a line passing through axes of the staff and spike, and that the shock of the blows given the spike is transmitted through the caging and around the cushioned lamp. By this construction 50 the device can be made of sufficient size and weight to be effective in the destruction of

bungs and at the same time sufficiently slender to pass through and be operative beyond the ordinary bung hole.

The wires 9 for conducting the electricity 55 to the lamp are conveniently passed down through the tubular staff and therefore do not interfere with the proper handling of the instrument.

As the device will have considerable 60 weight it will be convenient in practice to provide it with a counterbalancing weight, and the cord 10 to which this weight is to be attached, and a fraction only of which is shown, is passed over a pulley arranged at a 65 suitable height.

In use the spike end of the device is inserted 70 through the bung hole into the barrel and the spike used first to split the bung into pieces, after which the pieces are readily removed through the bung hole by impaling them on the end of the spike. The lamp affords all the necessary light to illuminate 75 the interior of the barrel for properly directing the spike when in the hands of the workman.

To replace an exhausted lamp it is only necessary to remove the parts 6, 7 and 8; which are shown to be one structure, after 80 which the worn-out lamp can be removed and a new one supplied.

What I claim and desire to secure by Letters Patent is:

1. An instrument for the removal of bungs from barrels comprising, in combination, a 85 staff, means for attaching an electric lamp to said staff, a lamp, an inclosing caging for protecting the lamp, a spike beyond the caging, the lamp being between the staff and the spike and lying within the line of the axes of the 90 staff and spike, and means for conducting electricity to the lamp.

2. An instrument for the removal of bungs from barrels comprising, in combination, a 95 staff, means for attaching an electric lamp to said staff, a lamp, a cushioning support for said lamp, an inclosing caging for protecting the lamp, a spike beyond the caging, the lamp being between the spike and staff and lying within the line of the axes of the 100 staff and spike, and means for conducting electricity to the lamp.

3. An instrument for the removal of bungs from barrels comprising, in combination, a staff having a chamber piece at its lower end, a lamp socket in said chamber piece, an electric lamp detachably connected to said socket, a structure comprising a collar, a caging for the lamp and a spike adapted to be removably attached to said chamber piece, the lamp lying in a line passing

through the axes of the staff and spike, and 10 conductors of electricity for said lamp.

In testimony whereof I affix my signature, in presence of two witnesses.

GUSTAV SPANNAGEL.
